UNITED STATES PATENT OFFICE.

CHARLES C. BEAM, OF CUMBERLAND, MARYLAND, ASSIGNOR TO THE WELLINGTON
GLASS COMPANY, OF CUMBERLAND, MARYLAND, A CORPORATION OF MARYLAND.

DESIGN FOR A LIGHT SHADE OR REFLECTOR.

45,980.

Specification for Design. Patented June 23, 1914.

Application filed January 10, 1914. Serial No. 811,474. Term of patent 3½ years.

To all whom it may concern:

Be it known that I, CHARLES C. BEAM, a citizen of the United States, residing at Cumberland, in the county of Allegheny and State of Maryland, have invented a new, original, and ornamental Design for Light Shades or Reflectors, of which the following is a specification, reference being had to the accompanying drawing, forming part thereof.

The figure is a side elevation of a light

shade or reflector showing my new design, the shade being substantially circular in cross-section.

I claim:

The ornamental design for a light-shade or reflector, as shown.

CHARLES C. BEAM.
